IGNITION BOOSTER SYSTEM

Floyd M. Du Laney, Chicago, Ill.

Application February 7, 1935, Serial No. 5,395

6 Claims. (Cl. 123—148)

This invention relates to ignition booster systems, and more particularly is directed to such systems embodied in the ignition circuits of internal combustion engines, used in automobiles, airplanes and the like.

In the preferred embodiment of the present invention, I provide a booster system automatically controlled by turning of the ignition switch for either connecting an additional auxiliary battery 10 into the ignition system to produce an increased voltage across the induction coil, or connecting the battery to a low voltage tap on the induction coil, whereby the voltage across the coil is increased. This increase of voltage produces a 15 hotter spark due to the increased current, and thereby assists materially in the starting of the engine.

It is well known that the car starter of an ordinary automobile produces a considerable voltage drop across the primary of the induction coil, especially if the car motor is cold and stiff, as in cold weather. This starter voltage thereby puts an increased load on the car battery proportional to the energy required by the starter motor, which 25 correspondingly decreases the voltage available for the induction coil, resulting in a proportionately weaker spark. It is to compensate for this condition that the present system has been developed.

Another object of the present invention is to provide a booster system operated directly by the ignition switch, whereby the increased voltage of the system can be availed of when cranking the engine by hand. This is a distinct advantage 35 possessed by the present system over previously known types of booster systems, in which the booster was only cut in upon energization of a starting motor or the like.

An additional advantage attained by the present invention is the provision of means for automatically cutting out either the auxiliary battery or the low voltage tap of the induction coil as the engine starts and becomes self-operative, whereby no switching means or the like is required for this 45 purpose. Thus no additional control or switching mechanism is required to insure operation of the booster system during starting of the engine, the system being automatically cut in by closing of the ignition switch and being automatically cut 50 out when the engine becomes self-operative. The human element of control is thus substantially eliminated.

Another advantage of the present invention is its applicability to ignition systems now in use, 55 it being adapted for ready connection thereto.

Also, its low initial cost and installation expense, with practically no up-keep expense, renders its use universally available to all car owners.

Other objects and advantages of the present invention will appear more fully from the following detailed description which, taken in connection with the accompanying drawing, will disclose to those skilled in the art the particular construction and operation of a preferred form of the present invention.

In the drawing:—

Figure 1 is a diagrammatic circuit illustrating the use of an auxiliary battery in an ignition booster circuit; and

Figure 2 is a diagrammatic circuit illustrating a modified type of ignition booster circuit.

Referring now in detail to Figure 1, I have provided the ordinary type of storage battery 5, having one terminal grounded, as at 6, and its other terminal leading to a switch contact 7 through the conductor 8. The switch contact 7 forms one contact of an ignition switch indicated generally at 9, the other contact 10 thereof being connected through conductor 12 to an ammeter 13. It is of course apparent that the ignition switch 9 might be incorporated directly within the ammeter, if desired.

From the ammeter 13, a conductor 14 is extended to the positive terminal of a dry cell or similar auxiliary battery 15, while a second conductor 16 is extended to a generator cut-out relay 17 connected through conductor 18 to the generator G, the opposite terminal of the generator being connected to ground in the usual manner.

From the positive terminal of the auxiliary battery 15 a conductor 19 is extended to a relay contact 20, while from the negative terminal of the battery 15 a conductor 22 is extended to a second relay contact 23. It is to be understood that the circuit is adapted for use with either a positive or negative to ground ignition system, and the particular terminal connections of the two batteries may be correspondingly reversed.

From the conductor 18, a conductor 24 is extended to an energizing coil 25 of a relay 26, and from the opposite end of the coil 25 a conductor 27 leads to ground. The relay 26 is adapted to energize an armature 28, which is normally held in closed position against contact 23 by means of a spring 29. The armature 28 is connected through conductor 30 to the induction coil 32, which may be any standard type of induction coil, and from the induction coil conductors 33 and 34 lead to the ordinary type of breaker and distributor generally shown at 35.

In the operation of the circuit shown in Figure 1, when it is desired to start the engine, which has its spark plugs or the like connected to the distributor 35, the ignition switch 9 is closed, 5 completing a circuit from the battery through contacts 7 and 10 and ammeter 13 to the conductors 14 and 16. A circuit from the conductor 14 extends through the auxiliary battery 15 and conductor 22 to contact 23, which is normally engaged by the armature 28. This completes 10 a circuit from battery 5 through the ignition switch 9, auxiliary battery 15 and armature 28 to the induction coil 32, the batteries 5 and 15 being thus placed in series whereby additional 15 voltage is provided to compensate for the voltage drop occasioned by the use of a starter motor or the like, which would ordinarily produce a corresponding voltage drop across the induction coil 32. By the provision of the present invention, 20 however, the auxiliary battery 15 compensates for this voltage drop, and provides a sufficient voltage, together with the battery 5, across the induction coil 32 to provide a hot spark at the spark plug contacts.

25 During starting of the motor, the combined voltage of the battery 5 and battery 15 is thus impressed across the induction coil. As the engine starts and becomes self-operative, the generator G is energized, producing a flow of current through conductors 18 and 24 to coil 25 of the relay 26. This produces energization of the relay 26, which in turn attracts the armature 28 into engagement with the contact 20 and out of engagement with contact 23. At the same 30 time, the generator relay cut-out 17 operates to cut in the conductor 16 with the conductor 18, whereby current is fed from the generator G to the battery 5 through the ammeter 13 and the ignition switch 9, in the usual manner.

40 It is thus apparent that the batteries 5 and 15 will be connected in series upon initial closing of the switch 9, whereby the armature 28, in engagement with contact 23, will provide for impressing the combined voltages of these batteries 45 across the induction coil 32, compensating for the voltage drop occasioned by the use of a starter motor or the like, so that a sufficient spark is produced by the induction coil enabling the motor or engine to be readily started. As the motor or 50 engine becomes self-operative, the generator G energizes the relay to cut out the battery 15 from the circuit, by moving armature 28 into engagement with contact 20 and out of engagement with contact 23. Thus, the auxiliary battery 15 55 is automatically cut into the ignition circuit when the ignition switch 9 is closed, and is automatically cut out of this circuit as soon as the engine becomes self-operative. These operations are effected with no manual control or supervision by the operator of the engine, and consequently the human element is substantially 60 eliminated from the control over this type of booster system, and the booster system is self-actuating and self-controlled throughout the operation of the ignition system.

65 Referring now to the circuit shown in Figure 2, I have provided a somewhat similar system, in which the auxiliary battery 15 has been eliminated, and a low voltage tap has been added to the induction coil. Corresponding parts of the circuit shown in Figure 2 will be identified by the numerals corresponding to the same parts as described in connection with Figure 1.

70 The conductor 14 leading from the ammeter 75 13 in this embodiment of the invention is con-

nected to the armature 28' of the relay 26, which armature is normally held away from the relay 26 by means of the spring member 29. The armature 28' is thus normally held in contact with the contact point 36, which is connected through conductor 37 to a low voltage tap 38 of the induction coil 32. The standard voltage tap of this induction coil is connected through conductor 39 to the contact 40. The primary coil and secondary coils of the induction coil 32 are connected, at their opposite ends to the conductor 42 leading to the circuit breaker 35, the secondary coil of the induction coil 32 at its opposite end being connected through conductor 43 to the circuit breaker and distributor in the usual manner.

20 In the operation of the circuit shown in Figure 2, when the ignition switch 9 is closed, the current from battery 5 is conducted through conductors 8 and 12 to the ammeter 13, and from the ammeter 13 through conductor 14 and armature 28' to contact 36. The battery current is thus led through conductor 37 to the low voltage tap 38 of the induction coil 32, and since the resistance of the primary coil of the induction coil 32 is thereby decreased, the current is increased, and thus a higher current is transmitted to the secondary of the induction coil 32, which current is transmitted through conductors 42 and 43 to the distributor 35, producing a hotter spark 25 at the plugs of the engine. It is therefore apparent that by providing the low voltage tap 38, the voltage across the induction coil 32 is increased to compensate for a voltage drop 30 caused by the starter motor or the like, and consequently the spark produced at the spark plugs of the engine by means of the breaker and distributor 35 is increased over the spark that would normally be obtainable without such a low voltage tap. As the engine becomes self-operative, the generator G is adapted to energize the coil 25 of the relay 26 through the conductors 18 and 24, and consequently draws the armature 28' into contact with the contact 40. At this 35 time the generator cut-out relay 17 closes, and the generator therefore supplies current through the conductors 18 and 16 to the conductor 14, thereby energizing the induction coil 32 in the usual manner.

40 It is thus believed obvious, in the circuit shown in Figure 2, that a hotter spark can be produced by means of the booster circuit including the relay 26 and armature 28', whereby a low voltage tap is cut into the induction coil 32 upon 45 initial closing of the ignition switch 9, and this low voltage tap is cut out and the standard voltage tap cut in when the engine becomes self-operative, without any further control being necessarily exercised by the operator of the vehicle.

45 It is also to be pointed out that by the provision of an ignition booster circuit controlled merely by closing of the ignition switch, it is possible to cut in, for example, in Figure 1, the auxiliary battery 15 when it is desired to crank the engine by hand, this battery being capable 50 of employing its voltage to supplement the voltage of the battery 5 through the induction coil while the car is being cranked by hand with the ignition switch on, the battery 15 being automatically cut out of the circuit when the engine 55 becomes self-operative.

60 The same is true in connection with the circuit shown in Figure 2, in which the low voltage tap 38 is automatically cut in when the ignition switch 9 is closed, so that upon cranking of the 65

car manually after the ignition switch has been closed, the low voltage tap will be cut in to provide a hotter spark at the engine. As the engine becomes self-operative, it is apparent that the 5 standard voltage tap will be cut in and the low voltage tap cut out by the self-operation of the engine.

It is therefore believed that the present invention provides a novel type of ignition booster system capable of automatic operation under the control of the ignition switch, substantially eliminating the human element in the cutting in or cutting out of such a booster circuit, and in addition providing a booster circuit capable of use 15 when the engine is being manually cranked. This particular type of booster circuit is adapted to compensate for the voltage drop produced across the induction coil by the use of a starting motor or the like, whereby a hotter spark 20 may be obtained than normally is obtainable during the cranking of an engine, either automatically or manually. This assists in starting of the engine during cold weather, when the motor may be cold and stiff, and the voltage drop 25 across the starter motor is proportionally greater.

If the induction coil of Figure 2 comprises a primary coil in series with a resistance, as known in practice, I may provide for boosting 30 the starting ignition circuit by providing a tap at the junction of the resistance and induction, whereby a relatively high initial current is provided, which tap may be cut out when the engine becomes self-operative, the resistance then 35 being cut in to reduce the current across the primary under normal running conditions.

I do not intend, however, to limit myself to the exact circuit connections which have been shown and described, but only in so far as defined by the scope and spirit of the appended 40 claims.

I claim:—

1. An ignition booster system for an internal combustion engine comprising an induction coil, 45 a battery, an ignition switch between said battery and said coil, an auxiliary battery between said switch and said coil and normally connected in series with said first battery upon closing of said switch, a generator, a relay energized by 50 said generator upon self-operation of said engine, and means responsive to said relay for disconnecting said auxiliary battery from said coil.

2. An ignition booster system for an internal combustion engine comprising a battery, an induction coil, an ignition switch between said coil and said battery, an auxiliary battery, an armature normally maintained in position for connecting said batteries in series to said coil, a relay, and means responsive to self-operation of 55 said engine for energizing said relay to move said armature into position for disconnecting said auxiliary battery from said coil.

3. The combination with an ignition booster system for an internal combustion engine, of means in said system normally operable upon closing of an ignition switch for increasing the current produced by the secondary of an induction coil, said means including an auxiliary source of current supply, and electromagnetic means responsive to self-operation of said engine for disconnecting said auxiliary current supply source. 5

4. An ignition booster system for an internal combustion engine comprising an induction coil, current supply means, a relay having a magnet, an armature, and front and back contacts for said armature, said armature normally engaging said back contact, an engine driven generator, said magnet being connected to said generator and energized upon predetermined operation of said generator to shift said armature from said back contact to said front contact, and circuit connections controlled by said armature engagement with said contacts, whereby a greater current is supplied to said coil from said current supply means when said armature is in engagement with said back contact than when said armature 20 is in engagement with said front contact. 25

5. An ignition booster system for an internal combustion engine comprising an induction coil with a primary coil circuit having a normal operating circuit connection including all the resistance of the primary coil circuit and a low resistance path including only a portion of the said coil circuit, a relay having a magnet, an armature and a back contact connected to said path and a front contact connected to said normal circuit connection, a battery connection controlled by said armature for closing the battery circuit with either the front or the back contact, and an engine driven generator, said magnet having a winding connected to said generator whereby the 40 armature is attracted to shift the battery connection upon predetermined engine-driven operation of the generator. 30 35

6. An ignition booster system for an internal combustion engine comprising an induction coil with a primary coil circuit having a normal operating circuit connection including all the resistance of the primary coil circuit and a low resistance path including only a portion of the 45 said coil circuit, a relay having a magnet, an armature and a back contact connected to said path and a front contact connected to said normal circuit connection, said armature normally being urged into engagement with said back contact, a battery connection controlled by said 50 armature for closing the battery circuit with said back contact, and an engine driven generator, said magnet having a winding connected to said generator whereby the armature is attracted to shift the battery connection to said front contact 55 upon starting of engine drive of the generator. 60
